TAB OPENER FOR A CONTAINER

William T. Saunders, Weirton, W. Va., assignor to National Steel Corporation

Filed May 26, 1971, Ser. No. 147,289

Term of patent 14 years

Int. Cl. D9—07

U.S. Cl. D9—256

FIG. 1 is a top plan view of a tab opener for a container showing my new design;

FIG. 2 is a bottom plan view of FIG. 1;

FIG. 3 is a sectional view of FIG. 1 taken along the line 3—3, and

FIG. 4 is a sectional view of FIG. 1 taken along the line 4—4.

I claim:

The ornamental design for a tab opener for a container, substantially as shown.
